VENDING MACHINE FOR PACKAGED ARTICLES

Charles L. Casey, Riverside, and Juddson B. Ryno,
Chicago, Ill., assignors to Reliable Metal Engineering Co., Chicago, Ill., a firm

Application April 18, 1947, Serial No. 742,424

8 Claims. (Cl. 312—69)

1

This invention relates to improvements in vending machines, particularly adapted, though not necessarily limited in use, for vending packaged sanitary napkins, and one of the objects of the invention is to provide in an improved machine of this character, means whereby the article may be readily delivered to the customer upon the deposit therein of a proper coin or token, to render the ejecting mechanism active.

Another object is to provide improved means for preventing the unauthorized extraction of another article after one has been delivered, until another proper coin is inserted.

A further object is to provide improved ejecting mechanism.

A further object is to provide improved means for preventing the insertion of a coin into the machine when the machine is empty, and which means is rendered inactive by the pressure of the articles or packages themselves.

A still further object is to provide improved means for storing additional articles or packages separately from the supply from which the articles are being vended.

Still another object is to provide an improved machine of this character, which will be simple, durable, compact in construction, and effective and efficient in operation.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating this invention, in which

Fig. 1 is a front elevation of a vending machine of this character, embodying the principles of this invention, and with the front or closure for the casing removed.

Fig. 2 is a detail vertical sectional view taken on line 2—2, Fig. 3, with parts broken away for clearness.

Fig. 3 is a detail view similar to Fig. 1, with parts omitted and with parts in section.

Fig. 4 is a detail sectional view on line 4—4, Fig. 5.

Fig. 5 is a detail sectional view on line 5—5, Fig. 4.

Fig. 6 is a horizontal sectional view taken on line 6—6, Fig. 3.

Fig. 7 is a view, partly in elevation, partly in section, and partly broken away, of the closure for the delivery outlet of the machine, and the supporting means therefor.

2

Referring more particularly to the drawings, the numeral 10 designates, generally, an enclosing casing, which may be of any desired size and configuration, and constructed of any suitable material. It is, however, preferably rectangular, and is provided with a closure 11, hinged at 12, which may be secured in a closed position by means of a suitable lock (not shown).

Within the casing is a partition 13 which forms 10 a support for the articles 14 that are being vended, and the partition is provided with an upright portion 15 that co-operates with the casing walls, to form a compartment 16, in which additional articles 17 may be stored. Another 15 partition 18 may also be provided to form a compartment 19 for holding still other objects 20. The partitions 15 and 18 terminate short of the wall 19a of the casing, to form a compartment 20a, in which latter the operating mechanism and 20 the ejector are removably disposed.

A closure member 21 for the delivery outlet is mounted upon a support 22, preferably in the form of a plate, having an opening 23 therethrough, through which opening the closure member 21 operates, in a manner to be described. The closure member is preferably mounted upon an arm 24 of a lever 25, which is pivotally supported intermediate its ends, as at 26, upon a fulcrum, such as between guide-ways 27, secured to the support 22 in any suitable manner, such as by means of rivets or fastening devices 28. The lower end of the lever is deflected forwardly, as at 29, for a purpose to be described.

A spring 30 anchored, as at 30a, tends normally to swing the lever 25 in a direction to move the closure member into a position to open a delivery outlet 31, through which opening the articles are delivered from the casing, and to also move the end 29 of the lever 25 into the position shown in

40 Figs. 1 and 3. The lever 25, and spring 30, being mounted upon the support 22, may be readily removed as a unit, by unfastening the fastening devices 32, 33 (Fig. 6), after which the support 22 may be withdrawn through the front of the casing. A guide-way 34 may be provided on the support 22, to receive an edge 35 (Fig. 3) of the casing, adjacent the delivery outlet 31, and a portion of the support 22 forms one wall of the outlet or delivery opening 31.

45 A shaft 36 is journaled in suitable bearings, and extends across the space or compartment 20a, one end projecting through an outer wall of the casing, and to which end is secured an operating handle 37, by means of which the shaft may be rotated. A coin carrier 38, having a seat therein

to receive a coin 39, is also carried by the shaft 36, and the coin seat is in alinement with the delivery end 49 of a coin chute 41 that opens through the front of the casing. A locking dog 42 co-operates with a shoulder 43, to lock the coin carrier and the shaft against rotation in one direction, until the coin raises the dog, in a manner well known in this art. The dog 42 may be gravity controlled, or controlled by a spring (not shown).

A spring 43a is anchored at one end, as at 44, and is connected at its other end, as at 44a, to the coin carrier 38, and tends normally to move the coin carrier and the shaft 36 in one direction. When the dog 42 is raised by the coin, the shaft and coin carrier may be rotated against the stress of the spring, and the spring, when the handle 37 is released, will return the parts to normal position.

Carried by the support 22, and pivotally mounted intermediate its ends, as at 45, is a closure for the coin chute 41, one end 46 thereof adapted to project across the coin chute, as shown in Fig. 1, when the other end 47 thereof is not engaged by the articles to be vended. A spring 48 tends normally to force the articles 14 to advance laterally forwardly, so as to position one of the articles in alinement with the delivery outlet 31, the article being forced against the partition or support 22, and at the same time engaging the member 47, to swing it about its pivot, to move the end 46 thereof out of position with respect to the coin chute 41, so that a coin can be inserted into the chute.

Carried by the shaft 36 is an ejector member 49, which is preferably in the form of an arm, and is disposed to project below the partition 13, and carried by the arm is a flange or abutment member 50 for the articles 14, the spring 48 urging the articles forwardly, so that when the foremost article contacts the support 22, it will be directly above the arm 49. When the shaft 36 is then turned by the handle 37, the co-operating parts being moved in a manner to be set forth, the article above the arm will be contacted thereby, and forced to project partially through the delivery opening 31, and into a position where it may be grasped by the operator (Fig. 5). The protruding article may then be drawn from the machine, and when the handle 37 is released, the spring 43a will return the ejector arm 49 and the coin carrier 38, so that another of the articles 14 may be moved into an ejecting position above the arm, by the spring 48 and the other articles in the vending compartment. It is to be understood that the closure 21 is first moved out of the way, so as to open the delivery outlet 31.

As the ejector arm 49 is raised to eject the article, the flange or abutment 50 will be moved into position within the path of advancing movement of the next article 14, to be engaged by the ejector when the partially ejected article is entirely removed through the delivery opening 31 (see Fig. 5). Since during this operation there will be no article in engagement with the coin chute closer member 47, it will swing by gravity so as to move the end 46 thereof across the coin chute 41, so that no coin can be inserted until another article contacts the member 47, to move its end 46 from across the coin chute, ready for the insertion of another coin to dispense another article.

When the partially ejected article 14 is removed through the delivery opening 31 (see Fig. 5), the flange or abutment member 50 will be in the posi-

tion shown in the figure, and it will be apparent that a subsequent article cannot be removed from the machine by the insertion of a tool or implement through the delivery opening 31.

The ejector 49 is provided with a shoulder 51 (Figs. 2 and 4), having a recess 52 that is adapted to be moved into a position in alinement with the end 29 of the lever 25, to receive such end and thereby permit the closure member 21 to move from across the delivery outlet 31, as shown in Fig. 5. The portions 53 and 53a of the shoulder, on opposite sides of the recess, are preferably of a cam shape, to co-operate with the end 29 of the lever 25, in a manner to be set forth. When the recess 52 is not in alinement with the end 29 of the lever 25, such end will engage the side of the ejector, and the latter will serve as a lock, or means for preventing the actuation or movement of the closure 21 in a direction that would open the outlet opening 31.

Carried by the ejector member 49, and in proximity to the recess 52, may be a member 54 which is pivotally mounted intermediate its ends, as at 55, on one side of the recess 52. A spring 56 tends normally to move the member 54 with respect to the shoulder 51, in a direction to cause it to engage a stop 57, on one side of its pivot, while the other end 58 of the member projects beyond the edge of the shoulder 51. The member 54 is so disposed with respect to the recess 52, and the end 29 of the lever 25, that when the recess 52 is in a position to receive the end 29 of the lever 25 (Fig. 5), such end will project into the recess and within the path of movement of the member 54, with the ejector.

In this position, the closure member 21 will assume the open position shown in Fig. 5, so that the article may be delivered through the delivery opening. A continued movement of the shaft 36, and ejector 49, in the same direction, will cause the member 54 to be rocked about its pivot 55, against the stress of the spring 56, and the member 54 will snap over the end 29 of the lever, and into the position shown in Fig. 4, on top of the end 29 of the lever 25.

Upon a reverse movement of the shaft 36, and the ejector 49, the free end of the member 54, being in contact with the stop 57, will become rigid with respect to the ejector, so that when it engages the end 29 of the lever, on the upper side of the latter, on this reverse stroke, it will cam and rock the lever 25, against the stress of the spring 30, and in the opposite direction, to move the closure member 21 from the open position shown in Fig. 5, to the closing position shown in Figs. 1 and 3, to close the delivery opening 31. The member 54 will then ride over the end 29 of the lever 25, back into the position shown in Fig. 2. When the ejector is moving to the position shown in Fig. 5, the flange or abutment 50 will assume the position shown in this figure, to arrest the advancing movement of the articles 14, and to form a shield or guard to prevent unauthorized removal of a subsequent article by the insertion of an implement through the delivery outlet 31.

When the ejector moves from the position shown in Fig. 5, to the position shown in Fig. 3, the flange or abutment 50 will move to the position shown, so as to permit another article to be advanced by the spring 48, to a position to contact the abutment, and to be engaged and ejected by the ejector when the latter is rocked after the insertion into the machine, of another proper coin or token.

A pawl 59 is provided to co-operate with a ratchet or toothed structure 60 on the coin carrier 38, to insure a full and complete movement of the coin carrier, the pawl being reversed by passing beyond a shoulder 61 at one end of the teeth 60, and into a recess 62 at the other end of the teeth, all as well known in this art. The coin carrier may be arrested in its movement by the engagement of a shoulder 63 with a stop 64 (Fig. 2), in a manner also well known in this art. The coin carrier 38 is arranged to discharge into a coin receptacle 65, removable from the casing when the closure 11 is opened.

The support 22, which carries the closure member 21, the lever 25, fulcrum 27, and coin slot closure member 47 (see Figs. 6 and 7), may be readily removed from the casing, as a unit, by removing the fastening devices or bolts 32, 33, so as to permit access to the ejecting and coin-controlled mechanism.

It is thought that the operation of this improved vending machine will be clearly understood from the foregoing description, but, briefly stated, it is as follows:

The normal position of the parts is that shown in Figs. 1 and 3, and the end 29 of the lever 25 will contact the side of the ejector 49. When a coin is inserted into the coin chute 41, it will be delivered to the coin carrier 38 (Fig. 2). Upon operation of the handle 37, the locking dog 42 will be raised to render the coin-controlled and operating mechanism active. Upon further rotation of the handle 37 in the same direction, the ejector 49 will be raised, the cam surface 53a will move along the top of the end 29 of the lever 25, to hold the closure 21 from opening under the stress of the spring 30, until the recess 52 is moved into a position in alinement with the end 29 of the lever 25. The spring 30 will then shift the closure 21 to an open position, as the end 29 of the lever will enter into the recess 52. The parts will then assume the position shown in Fig. 5.

A further movement of the ejector in the same direction will cause the end 58 of the member 54 to engage and ride over the end 29 of the lever 25, and subsequently snap thereacross. The article or package 14 to be delivered, will then assume the position shown in Fig. 5, as the cam surface 53 will engage the top of the end 29 of the lever 25, and hold the closure 21 open. The article can then be withdrawn.

With the parts in this position, should it be attempted to unauthorizedly remove another article or package by means of an instrument inserted into the delivery outlet 31, such removal will be prevented by reason of the fact that the flange or abutment 50 will have assumed the position shown in Figs. 4 and 5. As soon as the article is withdrawn, the spring 48 will advance the articles 14, so as to position another one above the ejector 49, and in engagement with the flange or abutment 50.

When the handle 37 is released, one end of the member 54 being in engagement with the stop 57, will cause it to become rigid with respect to the ejector, so that upon return movement of the ejector, the member 54 will engage and depress the end 29 of the lever 25, and force the closure 21 from the position shown in Fig. 5 back to the position shown in Figs. 1 and 3, against the stress of the spring 30.

The member 47, being weighted at its lower end, will, when there is no article 14 pressing thereagainst by the spring 48, swing into a posi-

tion to move the end 46 thereof across the coin chute to prevent insertion of another coin or token. When, however, the articles 14 are pressed against the end of the member 47, it will swing into a position to move the end 46 thereof out of the way, to open the coin chute to permit insertion of another coin or token, to dispense another article or package 14.

In the event that the operator should release the handle 37 when an article is projected partially through the delivery outlet 31, or when in the position shown in Fig. 5, the end of the closure 21 will be projected through the opening 23 in the support 22, and into engagement with the side of the article, but the article may be readily removed by grasping the exposed end and pulling the same through the opening. In this event, the closure 21 will yield, and no damage will be done to the article or package.

When the parts are in the position shown in Fig. 1, the pressure of the spring 48 will force the foremost article 14 against the support 22, and it will be held suspended above the ejector by friction, and the spring 48 will yield sufficiently, when the ejector is operated, to permit the foremost article to be moved thereby, from the position shown in Figs. 1 and 3 to that shown in Fig. 5.

While the preferred form of the invention has been herein shown and described, it is to be understood that various changes may be made in the details of construction, and in the combination and arrangement of the several parts, within the scope of the claims, without departing from the spirit of this invention.

What is claimed as new is:

1. In an article vending machine having a delivery outlet, an extended support for the articles, an injector mounted for rotation across an end of the support about an axis extending parallel to the longitudinal axis of said support and in a plane alined with said outlet, means for urging the articles from said end of the support into alinement with said delivery outlet and also with said injector, means for moving the injector to project an article through said outlet, a closure movable relative said outlet between open and closed positions and including an operating member, spring means biasing said closure to open position, and means embodying mechanism responsive in its operation to the actuation of said injector and cooperating with said closure operating member, for permitting said closure to move to open position under the force of said biasing means and to move said closure to closed position against the force of said biasing means.

2. In an article vending machine having a delivery outlet, an elongated support for the articles, an injector mounted for rotation across an end of the support about an axis extending parallel to the longitudinal axis of said support and in a plane alined with said outlet, means for continually urging the articles successively from the support into a position between the injector and the delivery end of said outlet, means for oscillating the injector, a closure movable relative said outlet between open and closed positions, said closure including an operating member, yieldable means independently urging said closure to open position, means cooperating with said operating member and responsive to the operation of the injector for permitting said closure to move to open position under the force of said urging means and to move said closure to closed position, against the force of said urging

means, and an abutment flange carried by the ejector and movable over said end of the support into and out of the path of advancing movement of the articles upon the said support as said ejector is moved to ejecting position and returned.

3. An article vending machine embodying a casing having a delivery outlet, an elongated support for the articles having an open end adjacent the delivery outlet, an ejector arm mounted for rotation across said open end of the support about an axis extending parallel to the longitudinal axis of said support and in a plane aligned with said outlet, means urging the articles along the support and successively into alignment with said outlet and said ejector arm, a closure mounted in the casing for opening and closing movement relative said delivery outlet, an operating member connected with said closure, resilient means independently biasing said closure to open position, and cam means on said ejector arm engageable with a part of said operating member remote from the closure, said cam means being formed for permitting said closure to move to open position when the ejector arm is moved to an ejecting position and to move said closure to a closed position against the force of said biasing means when the ejector arm is moved to an inoperative position.

4. An article vending machine embodying a casing having a delivery outlet, an elongated support for the articles having an open end adjacent the delivery outlet, an ejector arm mounted for rotation across said open end of the support about an axis extending parallel to the longitudinal axis of said support and in a plane aligned with said outlet, means urging the articles along the support and successively into alignment with said outlet and said ejector arm, a closure mounted in the casing for opening and closing movement relative said delivery outlet, an operating member connected with said closure, resilient means biasing said closure to open position, cam means on said ejector arm engageable with a part of said operating member remote from the closure, said cam means being formed for permitting said closure to move to open position when the ejector arm is moved to an ejecting position and to move said closure to a closed position against the force of said biasing means when the ejector arm is moved to an inoperative position, an abutment flange carried by said ejector arm and disposed for movement over said end of the support into and out of the path of movement of said articles as said ejector arm is moved to ejecting position and returned, and means for actuating said ejector arm.

5. An article vending machine embodying a casing having a delivery outlet, an elongated support for the articles having an open end adjacent the delivery outlet, an ejector arm mounted for rotation across said open end of the support about an axis extending parallel to the longitudinal axis of said support and in a plane aligned with said outlet, means urging the articles along the support and successively into alignment with said outlet and said ejector arm, a closure mounted in the casing for opening and closing movement relative said delivery outlet, an operating member connected with said closure, resilient means biasing said closure to open position, cam means on said ejector arm engageable with a part of said operating member remote from the closure, said cam means being formed for permitting said closure to move to

5 open position when the ejector arm is moved to an ejecting position and to move said closure to a closed position against the force of said biasing means when the ejector arm is moved to an inoperative position, an abutment flange carried by said ejector arm and disposed for movement over said end of the support into and out of the path of movement of said articles as said ejector arm is moved to ejecting position and returned, and means for rotating said ejector arm to ejecting position, and spring means connected with said rotating means to return the ejector arm from ejecting position.

6. In a vending machine having a delivery outlet, a support for the articles, an ejector movable adjacent an end of the support, means for urging the articles from the support into a position to be engaged and shifted by the ejector, a closure for the outlet movable into open and closed relations thereto, a pivotally mounted arm having one end connected with the closure and having the other end arranged for movement into and out of the operating path of the ejector, a cam member movable with the ejector, resilient means biasing the closure to one of said relations to the outlet and said other end of the arm into engagement with the cam member for controlling opening and closing movement of the closure, means for actuating the ejector, and one direction deflectable means carried by the cam member for yielding engagement with said other end of the arm and unimpeded passage of the last mentioned end thereby during ejecting movement of the ejector and camming engagement with said last mentioned end during retarding movement of the ejector.

7. In a vending machine having a delivery outlet, a support for the articles, an ejector movable adjacent an end of the support, means for urging the articles from the support into a position to be engaged and shifted by the ejector, a closure for the outlet movable into open and closed relation thereto, a pivotally mounted arm having one end connected with the closure and having the other end arranged for movement into and out of the operating path of the ejector, a plate cam member movable with the ejector, resilient means biasing the closure to an open position and said other end of the arm into engagement with the cam member for controlling opening and closing movement of the closure, one direction deflectable means carried by the ejector for yielding engagement with said other end of the arm and unimpeded passage of the last mentioned end thereby during ejecting movement of the ejector and camming engagement with said last mentioned end during retarding movement of the ejector, an abutment flange on the ejector movable into a position across the path of advancing movement of the articles upon the support while another article is being ejected, and means for actuating the ejector.

8. In a vending machine having a delivery outlet, a support for the articles, an ejector movable adjacent an end of the support, means for urging the articles from the support into a position to be engaged and shifted by the ejector, a closure for the outlet movable into open and closed relation thereto, a pivotally mounted arm having one end connected with the closure and having the other end arranged for movement into and out of the operating path of the ejector, a shoulder with a cam recessed edge carried by the ejector, resilient means biasing the closure

to an open position and said other end of the arm into engagement with said shoulder for controlling opening and closing movement of the closure, an auxiliary camming member pivotally mounted on said shoulder with one end extending outwardly thereof and swingable across part of the recessed portion of said edge, means positively limiting the swinging movement of said camming member in one direction while permitting swinging movement in the other direction to selectively cam the other end of said closure arm, said auxiliary camming member being arranged for unimpeded passage of said other end of the arm during ejecting movement of the ejector and camming engagement therewith
